(57) **CLAIM**

The ornamental design for a cellular phone case, as shown and described.

DESCRIPTION

FIG. 1 is a front and side perspective view of the cellular phone case showing my new design;

FIG. 2 is another perspective view of my new design;

FIG. 3 is a front elevational view of FIG. 1;

FIG. 4 is a side elevational view of FIG. 1, the opposite side being a mirror image;

FIG. 5 is a top plan view of FIG. 1;

FIG. 6 is a bottom plan view of FIG. 1;

FIG. 7 is a rear elevational view of FIG. 1;

FIG. 8 is a rear elevational view showing a second embodiment of my new design; and,

FIG. 9 is a rear elevational view showing a third embodiment of my new design.
